Inventor:

Heinrich Fischer

Heinrich Fischer

UNITED STATES PATENT OFFICE.

HEINRICH FISCHER, OF NUERMBERG, GERMANY, ASSIGNOR TO THE FIRM H. FISCHER & CO., OF NUERMBERG, GERMANY.

SOUNDING WHEELED TOY.

Application filed February 20, 1925, Serial No. 10,662, and in Germany November 20, 1924.

This invention relates to a sounding wheeled toy preferably in the shape of a car for an electric tramway the doors of which are alternately opened and shut, the movement of the car being stopped at the same time, the doors remaining shut when the car is running but being opened as soon as the car is stopped.

The car comprises further a signal bell which is operated when the motor car has stopped and the doors are opened.

An embodiment of the invention is shown, by way of example, on the accompanying drawing, in which:

15 Fig. 1 shows the toy car in side elevation.

Fig. 2 shows in side elevation the mechanism for operating the doors.

20 Figs. 3 and 4 are side elevations showing the clockwork, the elements of the same being in different positions and displaced 180° with regard to the positions of the same elements shown in Figs. 1 and 2.

Fig. 5 is a front view of the clockwork.

25 Fig. 6 illustrates a constructural detail. The sounding wheeled toy has the shape of an electric tramway car of the type commonly used in the United States. The tramway car has a door composed of two leaves 1, 2 (Fig. 2). The two door leaves 1, 2 are movably mounted in the car by means of rods 3, 4 coupled the one with the other by a connecting rod 5. To one end of said connecting rod 5 a two-armed lever 6 is hingedly connected adapted to pivot around an axle 7 fixed in the car. The lower end of the two-armed lever 6 engages with a bow 8 fixed on the rod 3 of the door leaf 1. The other end of the connecting rod 5 is attached to a bow 9 mounted on an arm 10 which is attached at the other end to the door leaf 2. With this bow 9 engages further the bent end of a driving rod 11 driven from a clockwork.

30 At one end of the car (Fig. 1) a bell 12 is arranged the clapper 13 of which is operated from the clockwork through the intermediary of a two-armed lever 14 adapted to oscillate around an axle 15 fixed in the car. The lower free end of said lever 14 is acted upon by a cam disk 16 of the clockwork.

35 On an axle 17 journaled in the housing 18 of the clockwork a frame 19 (Figs. 3-6) is mounted to oscillate and is rigidly connected with the driving rod 11 for the door

leaves 1, 2. This frame 19 carries at either side of its axle 17 an axle 22 and 23 carrying each a pinion 20, 21 respectively. On the axle 23 the cam disk 16 is keyed which operates the lever 14 at the upper end of which the clapper 13 is mounted (Figs. 4 and 3). The pinion 21 on this axle 23 is adapted to be brought in gear with a toothed wheel 25 keyed on the winding-up axle 24 of the clockwork. The axle 22 carries the two wheels 26 of the car and a pinion 20 on this axle 22 is adapted to be brought in gear with the driving wheel 27 of the clockwork. On the axle 23 which carries the cam disk 16 an arm 28 is mounted which has a longitudinal slot 29 traversed by the winding-up axle 24 of the clockwork. The upper end 30 of this arm 28 is bent at the right angles and engages with a cam disk 31 keyed on the winding-up axle 24 of the clockwork.

40 By the action of the weight of the vehicle the driving wheel 27 of the clockwork is brought in contact with the pinion 20 on the axle 22 which carries the wheels 26 of the vehicle so that these wheels are rotated and the car is started (Fig. 4). At every half rotation of the winding-up axle 24 the cam disk 31 comes in contact with the upper bent end 30 of arm 28 connected with the axle 23 of the oscillatable frame 19 so that this arm is raised and the frame 19 is oscillated in anti-clockwise direction, whereby the pinion 20 on the wheel axle 22 is brought out of gear with the driving wheel 27 (Fig. 3). 45 The movement is interrupted and the vehicle stops.

45 At the oscillating movement of the frame 19 the rod 11 attached to the same is moved in the direction of the arrow *a* (Fig. 2) 50 whereby the right door leaf is moved by the arm 10 in the direction of the arrow *b* that is to say opened. The connecting rod 5 which connects the two door leaves 1, 2 moves also in the direction of the arrow *b* 55 wherefrom results an oscillating movement of the two-armed lever 6 in the direction of the arrow *c* so that the rod 3 is moved in the direction of the arrow *d* pulling open the left door leaf 1.

50 By the oscillating movement of frame 19 the pinion 21 of the axle 23 which carries the cam disk 16 has been brought in gear with the clockwork wheel 25 (Fig. 3) so that this cam disk 16 is rotated in the direction 55

of the arrow *f* (Fig. 1) and makes the driving lever 14 of the clapper 13 oscillate in the direction of the arrow *g*. When the lever 14 slides off the cam disk 16 it jumps back 5 and the clapper 13 strikes against the bell 12. As soon as the cam disk 31 releases the upper bent end 30 of the movable arm 28 the frame 19 is returned by the action of the weight of the vehicle into its initial position. At this rotating movement the rod 11 10 and the intermediate element controlling the movements of the door leaves 1, 2 are made to move in opposite direction as before so that the door is being shut. At the same 15 time the alarm bell is stopped. When the oscillating movement of the arm 11 is finished and the door has been shut the pinion 20 operating the axle for the vehicle wheels 26 has again come in gear with the driving 20 wheel 27 of the clockwork and the vehicle continues to run until the cam disk 31 causes again, through the intermediary of arm 28, the oscillation of frame 19 so that the above-described proceedings are repeated. The 25 door may also be a one-leaf door or a hinged door. Each side wall or each end wall of the vehicle may have a door.

I claim:—

1. A sounding wheeled toy comprising in 80 combination, a body in the shape of a tram car, sliding doors in the side walls of said car, an alarm bell mounted at a convenient point in said car, a clockwork mechanism

for driving the wheel axle of said car, a lever system for operating the doors, a lever 35 system for operating the clapper of the alarm bell, a cam disk operated from said clockwork mechanism, and a frame oscillatably mounted in the housing of the clockwork mechanism operated from said cam 40 disk and designed to alternately operate said lever system for operating the doors and said lever system for sounding the alarm bell.

2. A sounding wheeled toy comprising in 45 combination a body in the shape of a tramway car, a sliding door in one side wall of said car, an alarm bell in said car, a clockwork mechanism in said car, an axle for the rear wheels of said car, a pinion on said 50 wheel axle, an oscillatable frame oscillated from said clockwork mechanism, two axles in said frame, an oscillatable rod for operating said door said rod being controlled directly from said frame, a pinion on each 55 frame axle the one pinion engaging with said pinion on the wheel axle when the oscillatable frame is in the one extreme position, a cam disk for acting upon the clapper of said alarm bell, said cam disk being rotated from the pinion on said second frame axle when the oscillatable frame is in the other extreme position.

In testimony whereof I affix my signature.

HEINRICH FISCHER.
